UNITED STATES PATENT OFFICE.

STANISLAUS WISNEWSKI, OF WARSAW, NORTH DAKOTA.

DOOR-LOCK.

No. 801,125.

Specification of Letters Patent.

Patented Oct. 3, 1905.

Application filed July 28, 1904. Serial No. 218,527.

To all whom it may concern:

Be it known that I, STANISLAUS WISNEWSKI, a citizen of the United States, residing at Warsaw, in the county of Walsh and State of North Dakota, have invented a new and useful Door-Lock, of which the following is a specification.

The invention relates to improvements in door-locks.

The object of the present invention is to improve the construction of door-locks and to provide a simple and comparatively inexpensive one of great strength and durability adapted to be readily operated by the proper key and capable of effectually preventing it from being surreptitiously operated by a tool or key not constructed for operating it.

With these and other objects in view the invention consists in the construction and novel combination and arrangement of parts hereinafter fully described, illustrated in the accompanying drawings, and pointed out in the claims hereto appended, it being understood that various changes in the form, proportion, size, and minor details of construction within the scope of the claims may be resorted to without departing from the spirit or sacrificing any of the advantages of the invention.

In the drawings, Figure 1 is an elevation of a portion of a door provided with a lock constructed in accordance with this invention. Fig. 2 is an elevation, the lock-casing being in section and the slideable bolt being shown retracted. Fig. 3 is a similar view, the slideable bolt being shown partially extended. Fig. 4 is a horizontal sectional view. Fig. 5 is a vertical sectional view on the line 5 5 of Fig. 2. Fig. 6 is a detail sectional view on the line 6 6 of Fig. 2. Fig. 7 is a detail perspective view of the tumbler. Fig. 8 is a detail view of the keeper. Fig. 9 is a detail view of the key. Fig. 10 is a detail view of the key-guide.

Like numerals of reference designate corresponding parts in all the figures of the drawings.

1 designates a door-lock casing designed to be mounted on a door 2, at the inner face thereof, and provided at its outer edge with an extension 3, which is secured against the edge 50 of the door, as clearly illustrated in Fig. 4 of the drawings.

Within the upper portion of the lock-casing is arranged a spring-actuated latch 4, disposed horizontally and provided at its inner

end with an enlarged portion 5, forming a hub 55 and having bearing portions 6 at opposite sides to fit in openings of the lock-casing. The latch, which is adapted to engage a keeper 7, is maintained normally in the position illustrated in full lines in Fig. 2 of the drawings 60 by means of a spring 8, having one end secured to a stud 9 and coiled around the same. The spring is provided with an arm extending outward from the coil and arranged above and engaging the latch at the outer portion 65 thereof. The latch is provided with a handle 10, arranged approximately horizontally and provided at its inner end with a shank 11, extending downward through a slot in the top of the casing and connected with the enlarged 70 inner end of the latch, being an integral part thereof, as clearly shown in Fig. 2. The shank of the handle is approximately L-shaped to offset the handle from the door a convenient distance for enabling it to be readily 75 grasped by the operator. The latch is released from the keeper by depressing the handle, and this operation may be conveniently performed by the operator when his arms are full by simply pressing downward 80 on the handle.

The handle 10 is arranged on the interior or at the inner face of the door, and the hub is provided with a rectangular opening for the reception of a spindle 12, provided at its 85 outer end with an integral handle 13, arranged horizontally, similar to that heretofore described, and connected with the outer end of the spindle by a substantially L-shaped shank 14. The outer end of the spindle is also provided with a flange or collar 15, which fits within an annular flange 16 of an outer escutcheon-plate 17. The spindle is adapted to be varied in length by means of a section 18, provided with an intermediate squared body 95 portion and having opposite threaded stems 19 and 20, the inner one of which is longer than the outer and screws into a threaded bore or socket 21 of the spindle. The outer threaded stem of the section receives a nut 22. 100 The section is capable of adjustment by screwing the inner stem into and out of the bore or socket of the spindle to vary the length of the latter to enable the lock to be applied to doors of different thicknesses and to adapt the 105 spindle to locks of different sizes. The opening of the enlarged portion or hub 5, which is rectangular to receive the squared portion

of the spindle, as clearly shown in Figs. 2 and 3 of the drawings, also snugly receives the intermediate portion of the section 18, as clearly shown in Fig. 5. The nut 22, which 5 engages the outer end of the hub or enlarged portion 5, firmly clamps the parts together, and there is no liability of the section 18 accidentally unscrewing when the parts are assembled.

10 The lock is provided with a slidable bolt 23, having a pair of notches 24 and 25 arranged to be successively engaged by a key, whereby two revolutions of the latter are required to complete the movement of the bolt in either 15 direction. These notches are formed in the lower edge of the bolt in the usual manner, and the upper edge of the bolt is provided with end and intermediate notches 26, 27, and 28, adapted to be engaged by a depending 20 tooth or portion 29 of a tumbler 30, mounted on a pivot-stud 31, and having a spring-arm 32 for holding it in engagement with the bolt. The spring-arm 32 is arranged at an acute 25 angle to the body portion of the tumbler and extends upward and bears against the enlarged portion of the spring-actuated latch. The body portion of the tumbler is provided with a depending approximately oval or elliptical, 30 arm 33, located at one side of the slidable bolt and arranged in the path of the key, whereby when the key is rotated the depending arm of the tumbler will be lifted to raise the tooth or engaging portion 29 of the tumbler out of a notch of the slidable bolt. The slidable bolt 35 is arranged within an opening of a guide 34, and it is provided with a longitudinal slot 35, receiving a stud 36, whereby the bolt is guided in its reciprocation. The bolt is also engaged by a bowed spring 37, secured between its 40 ends to the inner face of the removable face-plate of the lock-casing and having its arms free and engaging the slidable bolt. The lock is also provided with a curved key-guide 38, consisting of a thin substantially semicircular 45 plate mounted on a pair of posts 39 and arched over the keyhole, as shown. The keyhole 40 is provided with an angularly-disposed approximately U-shaped lower portion, and the web 41 of the key 42 is provided with an angularly-bent approximately U-shaped lower 50 portion to fit the keyhole. The web of the key is also provided with parallel kerfs 43, adapted to receive the curved guide and permitting the key to operate when introduced 55 into the lock at either side. The escutcheon-plate is provided with a keyhole 44 of the same shape as the keyhole of the lock-casing. The lock is provided with a tubular key-guide 46, extending through the door and projecting 60 a short distance beyond the same to facilitate the introduction of the key. The bottom of the horizontal key-guide is slotted for the passage of the web of the key, and the inner end of the key-guide is provided with later-

ally-extending arms 47, which are interlocked 65 with lugs or projections 48 of the lock-casing.

The keeper 7, which is constructed of metal, is provided with an angularly-bent body portion to receive the bolt, and it has a recess 49 at its upper portion to receive the latch or 70 catch 4. Adjacent to the recess 49 the keeper is provided with an enlarged projecting portion 50, presenting an inclined or beveled face for engagement with the latch or catch for guiding the same into the recess of the keeper. 75 The ends of the keeper are perforated for the reception of screws or other suitable fastening devices for securing it to the door frame or casing.

The lock is provided at the bottom with a 80 slidable latch 51, provided with a depending thumb-piece 52, connected with the latch 51 by a shank 53 and depending from the bottom of the lock-casing. The handle or thumb-piece is provided with a spring 54, arranged 85 to engage the lock-casing to prevent the latch 51 from accidentally slipping.

Having thus fully described my invention, what I claim as new, and desire to secure by Letters Patent, is—

90 1. In a lock of the class described, the combination of a lock-casing, a catch, a spindle provided at one end with a threaded socket, an adjustable section provided with an intermediate portion and having threaded stems, 95 one of the stems being fitted in the socket of the spindle, and a nut engaging the other threaded stem, substantially as described.

2. In a lock of the class described, the combination of a casing, a latch having an exterior 100 handle and provided with a hub having a polygonal opening, a polygonal spindle fitting in the opening of the hub and having an exterior handle, said spindle being also provided with a threaded socket, an adjustable section having 105 an intermediate polygonal portion fitting within the opening of the hub, said section being also provided with opposite threaded stems, one of the stems engaging the threaded socket, and a nut arranged on the other threaded stem and engaging the hub, substantially 110 as described.

3. In a lock of the class described, the combination of a casing, a latch provided with a hub arranged within the casing and extending through one side of the same, a spindle passing through the hub and provided at the opposite side of the casing with a shoulder, and an adjustable device engaging the spindle and the hub, substantially as described.

115 4. In a lock of the class described, the combination of a casing having a keyhole, a slid- 120 able bolt, a pivoted tumbler consisting of a body portion extending longitudinally of and provided with means for engaging the bolt, a resilient arm extending from one end of the body portion and arranged at an angle to the same for holding the said body portion in en-

gagement with the bolt, a depending curved arm located at one side of the bolt and adapted to be engaged by a key, and a flat plate located at the opposite side of the bolt in a plane parallel with the same and arched over the keyhole and arranged in the path of the key.

5 In testimony that I claim the foregoing as

my own I have hereto affixed my signature in the presence of two witnesses.

STANISLAUS ^{his} WISNEWSKI.
